DESIGN FOR AN ADHESIVE TAPE DISPENSER

Donald E. Dailey, Philadelphia, Pa.

Application March 14, 1946, Serial No. 127,490

Term of patent 14 years

(Cl. D74—1)

To all whom it may concern:

Be it known that I, Donald E. Dailey, a citizen of the United States, residing in Philadelphia, in the county of Philadelphia and State of Pennsylvania, have invented a new, original, and ornamental Design for an Adhesive Tape Dispenser, of which the following is a specification, reference being had to the accompanying drawing, forming part thereof.

The figure is a side perspective view of an adhesive tape dispenser, showing my new design, the opposite side presenting substantially the same appearance as the side shown.

I claim:

The ornamental design for an adhesive tape dispenser, as shown and described.

DONALD E. DAILEY.
